CLAIM

The ornamental design for a beverage dispenser, as shown and described.

DESCRIPTION

FIG. 1 is a side elevational view of a beverage dispenser showing our new design;

FIG. 2 is a top plan view thereof;

FIG. 3 is a front elevational view thereof;

FIG. 4 is a rear elevational view thereof;

FIG. 5 is a cross-sectional view thereof taken on line 5—5 of FIG. 1; and

FIG. 6 is a bottom plan view thereof.

FIG.5.

FIG.6.
